203,495

ELECTRICALLY OPERATED HAND HELD SHOE POLISHER

Edwin Fitzwater, Little Falls Township, Passaic County,
N.J., assignor to The Regina Corporation, Rahway,
N.J., a corporation of Delaware

Filed Aug. 31, 1964, Ser. No. 81,511

Term of patent 14 years

(Cl. D9—2)

Fig. 1

Fig. 2

Fig. 3

Fig. 4

FIG. 7

FIG. 5

FIG. 8

FIG. 6

FIG. 9

FIG. 1 is a top plan view of an electrically operated hand held shoe polisher showing the handle in open position showing my new design.

FIG. 2 is a side elevational view thereof.

FIG. 3 is a top plan view thereof, showing the handle in closed position.

FIG. 4 is a side elevational view thereof.

FIG. 5 is a rear elevational view thereof.

FIG. 6 is a front elevational view thereof.

FIG. 7 is a bottom plan view thereof, showing the handle in open position.

FIG. 8 is a bottom plan view thereof showing the handle in closed position, and

FIG. 9 is a rear elevational view thereof.

I claim:

The ornamental design for an electrically operated hand held shoe polisher, as shown.
